LINGERIE TAPE

Horace W. Sidebotham, Philadelphia, Pa.

Application September 8, 1934, Serial No. 743,201

1 Claim. (Cl. 139—420)

My invention relates to certain new and useful improvements in textile fabrics and more particularly to a tape adapted especially for use as lingerie tapes or shoulder straps or the like.

It has been the practice in making shoulder straps for lingerie or the like, to form them of ordinary thin silk fabrics or silk cloths, which, according to the usual practice, are cut into narrow strips of a width slightly greater than twice the desired width of the shoulder straps or tapes or "he like, and these strips of the silk fabric are then folded longitudinally and their juxtaposed cut edges in-turned and then seamed by a suitable line or lines of sewn stitches, thereby producing a relatively narrow band or tape of a two-ply formation with the longitudinal edge or edges bound by a row or rows of sewn stitches.

The object of my present invention is to form lingerie tapes for shoulder straps and the like, which will have the appearance of the cut-and-sewn lingerie tapes hereinabove described but which will be integrally woven in a two-ply formation so as to give the appearance of a cut-and-sewn tape, and which will be cheaper and yet superior thereto.

A further object of my invention is to produce integrally woven tapes of this character which will be inexpensive to produce and which will possess greater durability and certain other desirable characteristics and qualities not present in the cut-and-sewn tape construction heretofore used.

With the above and other objects in view, which will appear more fully from the following description and accompanying drawing, my invention consists of a tubular woven textile tape structure formed of relatively loose or untwisted and relatively dull warps having no twist or but a slight amount of twist, and weft threads having a substantial twist and extending alternately through the two different plies of said warps of the fabric structure;—that is, woven alternately through two different sheds of said warps;—and a relatively few bright or lustrous rayon or silk warp threads grouped near each of the two longitudinal selvages of the fabric structure, but spaced inwardly therefrom to a slight extent, and shed with each two successive picks of the weft instead of alternately as the first hereinabove mentioned dull warp threads, thereby to cause the two plies to merge into a single ply throughout the zones of these two groups of lustrous rayon or silk warps, thereby simulating the appearance of sewn stitches in these zones.

My invention further consists of other novel

features as well as certain novel details of construction, all of which will appear more fully from the following description and accompanying drawing.

For the purpose of illustrating my invention, I have shown in the accompanying drawing, one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawing in which like reference characters indicate like parts:

Figure 1 represents a top plan view of a small piece of the tape structure embodying my invention shown on a much enlarged scale.

Figure 2 represents a section generally on line 2—2 of Figure 1.

Figure 3 represents a section generally on line 3—3 of Figure 1.

Figure 4 represents a section generally on line 4—4 of Figure 1.

It will be understood that in the drawing, the proportions are not accurate and that particularly the sectional views are to be recognized more as schematic representations, since in the actual structure the several plies lie closer to each other than is shown in the drawing;—the latter being more for purposes of illustration of the weave and structure rather than for the exact dimensional relationship or spacing of the parts.

The fabric structure of my present invention includes two sets of relatively dull and relatively untwisted or relatively twist-free rayon warp yarns 5 and 6 respectively, each set being shed separately of and alternately to the other set, but in conjunction with the same relatively twisted cotton weft thread 7 extended alternately (back and forth) through the two different and alternating sheds of the two different sets of warps 5 and 6.

Near each of the selvages, designated generally by the numerals 8 and 9, a relatively few (two, four or six) warp threads 10 are provided of a more lustrous rayon or silk or the like, in place of the dull rayon warps 5 and 6 comprising the rest of the warp structure of the fabric;—these lustrous rayon or silk warps 10 being grouped together in two separate groups (as indicated particularly in Figures 1 and 2) a slight distance inwardly of the selvage edges but spaced

generally equally from their respective selvage edges.

The lustrous rayon or silk warps 10, just as the relatively duller rayon warps 5 and 6 are 5 relatively untwisted or free of twist, or but slightly twisted, so as to spread out more or less flatly over the relatively more twisted cotton weft threads 7 as indicated more particularly in Figures 1 and 2;—while the weft thread 7 is relatively highly twisted so as more firmly to retain 10 its form or its cross section, and thereby to be more completely concealed by the softer warps.

The lustrous rayon or natural silk warps 10 being relatively more lustrous than the relatively dull rayon warp threads 5 and 6, produce 15 a contrast in the zones the warp threads 10. This contrast, due to a difference in luster or sheen, is augmented by the passage of the warp threads 10 through both two successive (back and forth) picks or traverses of the weft 7, which units the two plies into a single ply in the zones of the warps 10. This is done by keeping 20 the shed of the warps 10 open for two successive picks or traverses of the weft 7, that is, for a back and front movement or a complete cycle of the shuttle, while the rayon warps 5 and rayon warps 6 are shed separately and alternately;—one set of warps (5) receiving the weft in one direction of the shuttle and the other set of 25 warps (6) receiving the weft in the reverse direction of the shuttle. This relation of the warps 10, accentuates the contrast and binds the two plies firmly together near the selvage edges of the fabric structure, thereby also giving 30 reinforcement to the edges.

By the fabric structure of my present invention, a tape is produced having the two plies of generally tubular formation, but maintained in a flat condition, and also reinforced, by two 35 small groups of warp threads extending through both plies and presenting a simulation of sewn stitches near these selvage edges.

By reason of the twist in the weft and absence of twist in the warp and further by reason 40 of the fact that the weft threads are of cotton, while the warp threads are principally of rayon, the latter are caused substantially to cover the weft threads so as to conceal the same and to give a soft smooth surface on both faces 45 of the fabric structure.

While the warp threads 5 and 6 have been described as a dull rayon, it is to be understood that any other relatively dull multi-filament

yarn may be employed, as for instance, cellulose acetate yarns or other regenerated cellulose yarns or cellulose derivative yarns which are either naturally dull or which have been de-lustered. Likewise, the lustrous or bright warps 5 10 may also be formed of acetate yarn or other regenerated cellulose derivative yarns or even silk;—the essential requirement being in this regard that there be contrast between the warp threads 10 and warp threads 5 and 6 by virtue 10 of difference in luster or sheen. The warp threads 5 and 6, as stated, each comprise many individual filaments which are related to each other in each strand or yarn with but very little or no twist. The warp threads 10 are likewise 15 formed of a great many individual filaments and also preferably related to each other without twist or with very little twist.

I am aware that my invention may be embodied in other specific forms without departing 20 from the spirit or essential attributes thereof, and I therefore desire the present embodiment to be considered in all respects as illustrative and not restrictive, reference being had to the appended claim rather than to the foregoing description to indicate the scope of the invention.

Having thus described my invention, what I hereby claim as new and desire to secure by Letters Patent is:

Lingerie tape or the like comprising two separate sets of relatively dull multi-filament regenerated cellulose warp threads relatively free of twist, a relatively twisted cotton weft thread extending alternately through said two sets of dull warp threads and forming therewith two 30 separate plies in continuation of and in generally tubular relation to each other and two groups of relatively lustrous multi-filament regenerated cellulose warp threads devoid of any substantial twist spaced inwardly a slight distance from the respective longitudinal edges of the tape and having each set thereof common to two successive picks or traverses of the weft and extending completely through both plies of the 35 structure, thereby merging the two plies of the otherwise tubular fabric structure into single plies throughout the narrow longitudinal zones of said two sets of lustrous warp threads and thereby reinforcing the marginal portions of the tape and forming contrasting lines on both faces 40 of the tape near the edges thereof in simulation of sewn stitches.

HORACE W. SIDEBOOTHAM.
